To all whom it may concern:

Be it known that I, Joseph F. Woerner, a citizen of the United States, residing at Houston, in the county of Harris, in the State of Texas, have invented a new, original, and ornamental Design for a Clamp, of which the following is a specification, reference being had to the accompanying drawings forming a part thereof, wherein:

Figure 1 is a side elevational view of a clamp showing my new design;

Figure 2 is a top plan view of the same;

Figure 3 is a bottom plan view of the same; and Figure 4 is an end elevational view, looking at the right hand end of the clamp as illustrated in Figure 1.

I claim:

The ornamental design for a clamp, as shown.
